Bradford Morris & Brainerd
ATTORNEY.

UNITED STATES PATENT OFFICE.

IRA T. SWARTZ, OF INDIANAPOLIS, INDIANA, ASSIGNOR TO SWARTZ ELECTRIC COMPANY, OF INDIANAPOLIS, INDIANA, A CORPORATION OF INDIANA.

SWITCHBOARD-SUPPORT.

1,360,247.

Specification of Letters Patent. Patented Nov. 23, 1920.

Application filed November 17, 1919. Serial No. 338,750.

To all whom it may concern:

Be it known that I, IRA T. SWARTZ, a citizen of the United States, residing at Indianapolis, in the county of Marion and State of Indiana, have invented certain new and useful Improvements in Switchboard-Supports, of which the following is a specification.

This invention relates to supports, more especially to a support for switch boards, and has among its objects the production of a support which will allow a switch board slate to be easily inserted into the support, which will securely hold the slate in place, and which can be made at a low cost.

Hitherto such switch supports were constructed with a groove formed on the inner surface of the upright and horizontal arms of the support. This groove was of such a width that the switch board slate fitted within the same and was held thereby. The patterns used for forming the mold for the casting of such supports were necessarily complicated on account of the necessity for forming cores for the groove, and the support was of considerable thickness, much greater than that necessary to support the slate, all of which increased the cost of such supports.

By my invention I obviate the necessity of making relatively complicated patterns and am enabled to reduce the width and consequently the weight of the support to a large extent (sometimes as much as one-half). In carrying the objects of my invention into effect I form a support without a groove and of a width generally about that of the slate to be supported; apertures are formed along the inner surface of the supporting arms and spools are inserted in such apertures. Flanges on the spools serve to hold the slate in place.

Referring to the accompanying drawings forming a part hereof and in which similar reference characters denote similar parts,

Figure 1, illustrates a front elevation of my improved switch board support showing a slate in place,

Fig. 2, an end elevation thereof, and

Fig. 3, a section taken as indicated in Fig. 1.

The support 1, which holds the switch board slate 2, is formed with a pedestal 3. From the upper end of the support, substantially horizontal arms 4 extend in opposite

directions and on the ends of such horizontal arms 4 are formed vertical arms 5. The inner surface of the support formed by such horizontal and vertical arms is of a shape suitable for the reception of the slate to be supported, which in this case is rectangular. The inner surfaces of the arms are smooth and a plurality of oblique holes or apertures 6 formed in any suitable manner, are provided at suitably spaced points.

Into such holes are fitted the shanks 7 of spools having flanges 8 fixed to the ends thereof. The holes 6 and shanks 7 are so proportioned that they fit each other snugly, the shanks being of such length that the flanges 8 make close contact with the arms 5. In assembling a switch board, spools are first inserted into their holes and the slate slid into place as usual, the flanges and the spools gripping the arms 5 and holding the slate 2 being supported in securely fixed relation to the arms.

Although I have described a specific embodiment of my invention wherein a switch board plate is supported on a suitable pedestal, my invention should not be limited to such specific example, since it is obvious that other suitable members may be supported by such an arrangement. The arms need not be horizontal and vertical but may have any inclination desired. The inner surfaces of the supporting arms need not necessarily form right angles, as shown in Fig. 1, nor need the member to be supported be rectangular. These and other changes which may be made in the various details, I consider to be embraced in my invention.

Having thus fully described my said invention, what I claim as new and desire to secure by Letters Patent, is:

1. A switch board support comprising supporting arms, obliquely formed apertures therein, and spool members adapted to be inserted in said apertures to securely hold a switch board slate on said arms.

2. A switch board support comprising supporting arms, apertures therein, and spool members comprising shanks and flanges adapted to be inserted in said apertures to securely hold the switch board slate on said arms.

3. A switch board support comprising supporting arms, apertures therein, spool members comprising shanks and flanges adapted to be inserted in said apertures to securely hold the switch board slate on said arms.

hold the switch board slate on said arms, said shanks fitting into said apertures, and said flanges contacting with the surfaces of said arms and of said slate.

5. A support comprising an arm, an aperture therein, a spool in said aperture and flanges on said spool adapted to grip said arm and to hold the member to be supported in fixed relation to said arm.

In witness whereof, I have hereunto set my hand and seal at Indianapolis, Indiana, this 14th day of November, A. D. nineteen hundred and nineteen.

IRA T. SWARTZ. [L. S.]
